UNITED STATES PATENT OFFICE

103,726

DESIGN FOR A WHEEL

James M. Kerr, Royal Oak, Mich., assignor to
Kelsey-Hayes Wheel Company, Detroit, Mich.,
a corporation of Delaware

Application August 17, 1936, Serial No. 64,456

Term of patent 14 years

To all whom it may concern:

Be it known that I, James M. Kerr, a citizen of the United States of America, residing at Royal Oak, in the county of Oakland and State of Michigan, have invented a certain new, original, and ornamental Design for a Wheel, of which the following is a specification, reference being had therein to the accompanying drawing, forming a part thereof, in which Figure 1 is a perspective view of the wheel body; Figure 2 is a fragmentary front elevation of the wheel; Figure 3 is an axial section therethrough; and Figure 4 is a cross section on the line 4—4 of Figure 2.

The present design comprises as the principal and dominating features thereof that portion of the wheel body shown in full lines formed with alternate portions axially offset in opposite directions with respect to each other, and each of the portions extending radially to adjacent the rim; and also each of the portions opening circumferentially at its opposite ends.

I claim:

The ornamental design for a wheel substantially as shown and described.

JAMES M. KERR.
